UNITED STATES PATENT OFFICE.

PHILIP HANAVAN, OF OAKLAND, CALIFORNIA.

FEED-ROLL.

SPECIFICATION forming part of Letters Patent No. 325,339, dated September 1, 1885.

Application filed June 1, 1885. (No model.)

To all whom it may concern:

Be it known that I, PHILIP HANAVAN, of 5
Oakland, Alameda county, State of California,
have invented an Improvement in Feed-Rolls
for Wood-Working Machinery; and I hereby
declare the following to be a full, clear, and
exact description of the same.

My invention relates to certain improvements
in feed-rolls for wood-working ma- 10
chinery.

It consists of removable adjustable teeth,
and a means for securing them in the roll,
which will be more fully explained by reference
to the accompanying drawings, in which—

15 Figure 1 shows a feed-roll complete. Fig.
2 shows a modification of the same. Fig. 3
shows the manner of fixing the teeth in the
roll. Fig. 4 is a section of the modification.

A is the hub of the feed-roll provided with
20 flanges B, between which the teeth C are to be
held. These teeth are formed of strips of
steel cut from a bar, three-sixteenths of an
inch thick and of a width sufficient to allow
them to just fit between the flanges B. They
25 are cut of such a length as to extend from the
hub outward between the flanges, projecting
beyond the rims of the flanges as far as may
be desired, having their outer edges beveled
or ground, so as to present sharp edges, as
30 shown. These plates have holes or openings
punched through them, and the flanges B have
indentations formed in them on the inner sides,
so that the metal by which the teeth are held
in place and fixed to the roll will be held firmly
35 and prevented from slipping around between
the flanges. In order to fix these teeth in their
places, I bore a hole in a wooden block of a
size sufficient to admit the end of the hub,
which is outside of the flanges. A channel is
40 cut concentric with this hole, so that its inner
edge is just flush with the peripheries of the
flanges B when the hub is set vertically in the
central hole. A series of short wooden strips
are then set in this channel, projecting up be-
45 tween each pair of teeth all around the pe-
riphery of the flanges, against which the
inner sides of the strips rest, thus making,
with the teeth, an inclosure that may be made
tight with putty and bound with a strip of
50 cloth. Within the rims and around the hub
fluid babbitt or other suitable metal may be
poured through the holes in the upper end of

the hub or flange. This metal runs around
through the openings in the plates forming the
teeth, and fills the spaces between them flush 55
with the outer periphery of the rims, thus
leaving the sharpened edges of the teeth pro-
jecting beyond the rims.

The indentations and holes made in the hub
and the flanges will hold the teeth, and the 60
intervening metal prevents them from slipping
around between the hub and the flanges.

In some cases a single flange may be made,
as shown in Fig. 2, having a channel or groove
formed concentric with and parallel with the 65
shaft-opening, and between it and the exterior
rim. Holes are made through the exterior
rim, and the teeth (which are made of round
steel, with their outer ends flattened and
spread out, so as to form wide chisel points or 70
teeth) have their inner ends inserted through
these holes, so as to rest against the inner cir-
cumference of the channel before described.
Melted metal is then poured in this channel
around the inner ends of the teeth, which are 75
notched or formed so as to be held by the
metal, and the device is complete.

In the ordinary construction of feed-rolls
the teeth are formed by grooves or channels
cut across the face of the roll by a milling-ma- 80
chine, leaving the teeth projecting upward;
but these being formed in the metal itself soon
wear dull, and the roll must either be thrown
away or else again run through the milling-
machine, which takes time. This construc- 85
tion also makes it very expensive to make
them of steel. In some cases sharp-pointed
teeth have been inserted in holes formed in
the rim of the roll, but these teeth are apt to
split the lumber, and are not satisfactory. 90

With my device, whenever the teeth become
worn they may be easily removed by simply
melting out the soft filling-metal, and then
they can be resharpened and set a little farther
out between the hub and the flanges, after 95
which melted metal is again poured in and
the teeth are firmly fixed. Teeth formed in
this manner may be made of steel, can be
easily sharpened, and may be tempered so
that they will last for a long time. 100

Having thus described my invention, what I
claim as new, and desire to secure by Letters
Patent, is—

1. In a feed-roll for wood-working machin-

ery, the roll having the independent adjustable flat-edged teeth projecting around its periphery, and having their inner ends secured by a filling of fusible metal poured into the 5 channel between and around the independent teeth, substantially as herein described.

2. In a feed-roll for wood-working machinery, the hub having a rim or flanges with their intervening channel, in combination with independent adjustable teeth or plates set into the rim, and a filling of fusible metal poured in and around said teeth, whereby they are held, substantially as herein described.

3. In a feed-roll for wood-working machin-

ery, a hub having a rim or flanges projecting 15 therefrom, and having holes or indentations in its sides, in combination with independent radially-placed teeth or plates having openings, perforations, or indentations within the channel, and a filling of fusible metal surrounding said teeth, substantially as herein 20 described.

In witness whereof I have hereunto set my hand.

PHILIP HANAVAN.
